(57) **CLAIM**

The ornamental design for a “container for glue,” as shown and described.

DESCRIPTION

FIG. 1 is a front perspective view of a container for glue showing our new design;

FIG. 2 is a front elevational view thereof, the rear elevational view being the same;

FIG. 3 is a side elevational view thereof, the opposite side elevational view being the same;

FIG. 4 is a top plan view thereof;

FIG. 5 is a bottom plan view thereof;

FIG. 6 is a cross-sectional view taken along line 6—6 of FIG. 2;

FIG. 7 is a cross-sectional view taken along line 7—7 of FIG. 3; and,

FIG. 8 is an exploded perspective view of the container for glue.
